(57) **CLAIM**

The ornamental design for a container upper section, as shown and described.

DESCRIPTION

FIG. 1 is a perspective view of the container upper section of our design.

FIG. 2 is a left side elevation view thereof.

FIG. 3 is a right side elevation view thereof.

FIG. 4 is a front elevation view thereof, the rear elevation view being a mirror image thereof.

FIG. 5 is a top plan view thereof.

FIG. 6 is a bottom plan view thereof; and,

FIG. 7 is an alternate embodiment of the container upper section showing the left side elevation view, the other views being the same.

The broken line showing of the lower portion of a bottle is for illustrative purposes only and forms no part of the claimed design.
